UNITED STATES PATENT OFFICE

2,214,030

BUTTON

Joseph L. Pereles, Milwaukee, Wis.

Application April 8, 1939, Serial No. 266,895

6 Claims. (Cl. 40—10)

My invention relates to improvements in buttons, the term "button" being employed in its generic sense.

Objects of my invention are to provide an improved button of non-frangible material, transparent in whole or in part, and adapted for purposes of display; to provide a button having a form-sustaining transparent cap, a portion of which is adapted to serve as a magnifying lens; to provide a button in which the cap and the backing are spaced from each other except at the margins to form a cavity within which fabrics and similar materials may be displayed without compression; to provide a button having a cap, a backing, and a connecting hub formed integrally of transparent material, and provided with a cavity in which various articles may be displayed; to provide a cavitated button containing an article to be displayed, and otherwise composed wholly of transparent plastic, such, for example, as acetate or synthetic resins.

In the drawing:

Figure 1 is a plan view of one form of my improved button, with one side of the cap partially broken away to disclose an insert of fabricated material.

Figure 2 is a sectional view of the same, drawn to line 2—2 of Figure 1.

Figure 3 is a view similar to Figure 1, illustrating a pictorial insert.

Figure 4 is a sectional view drawn to the same plane as Figure 2, but showing a modified form of construction, in which the central portion of the cap is spaced from the backing sufficiently to receive a fabricated insert with projecting fibers or so-called nap.

Figure 5 is a view similar to Figure 4, and showing a modified form of cap provided with a central bull's-eye, capable of a high degree of magnification, whereby the contents of the cavity, whether fabric or pictorial, may be magnified when viewed from the proper angle.

Figure 6 is a view, partly in perspective and partly in section, showing a modified back member.

Like parts are identified by the same reference characters throughout the several views.

In Figures 1 and 2 the cap 10 is formed of plastic, preferably molded with a convex outer surface and a rounded margin 11. The rear or inner face is socketed to receive a suitable back plate 12, which may be molded of the same material, and provided with a hub 13 having apertures 14 therein to facilitate stitching the button to a garment. The form of the back plate is not

essential. Any of the back plates shown in the other views may be substituted.

The terms "plastic" and "plastics" as herein used are defined and limited to those substances known to the modern commercial art by those names as non-frangible, substantially incombustible, form maintaining material capable of being made transparent, translucent or substantially opaque, dependent upon the presence or absence of coloring or opaque material not essential to the characteristics of the material as a plastic. Plastics, as so defined, are soluble in alcohol, benzine, acetone or other volatile members of the ketonic and aldehyde groups.

Between the cap 10 and the back plate 12, material to be displayed may be interposed in Figures 1 and 2. This material to be displayed comprises a piece or disk of fabric 16, preferably corresponding to or matching the garment to which it is intended to be secured.

The button may be assembled by inserting the disk 16 in the cap socket, then applying the backing 12 and cementing its margin to the rim 11, or preferably integrally connecting it by applying liquid plastic at the joint 17 and allowing it to harden.

In place of the fabric disk 16, I may substitute a picture card 18, as illustrated in Figure 3, or any other device or material to be displayed.

In Figure 4, I have illustrated a concavo-convex cap 10a, having a rim portion 11a shouldered at 20 to receive the back plate or disk 12a, the back plate being thus spaced at a substantial distance from the central portion of the cap 10a, whereby a piece 22 of velvet or similar material may be placed on display without having its nap compressed by the cap. Preferably, the curvature of the cap is such as to magnify the fabric or any picture or other object contained in the cavity 23. The rim 11a may be of the so-called "snap-on" type, the margin of the back plate having the form of an inverted cone.

If desired, the material to be displayed may be secured to the backing by any suitable means adapted to prevent it from shifting in the cavity 23. If the backing is formed of plastic, I preferably apply liquiform plastic to its surface before applying the material to be displayed. When this plastic cement hardens, it securely connects the material to be displayed with the backing.

In Figure 5, I have illustrated a cap having a relatively flat annular portion 10b encircling a central bull's eye 25. The rim 11b of this cap is similar to that illustrated in Figure 4, although an interior shoulder is not necessary unless em-

ployed for spacing the back plate from the portion 10b. The back plate 12b has its top surface provided with a central recess 27 of any desired outline, but preferably circular in form. This recess is adapted to receive the material to be displayed, and the surface 28 of the back plate may be colored or provided with an annulus 29 of colored paper or other suitable material. Its exposed surface may be either ornamental or any solid color to provide a mounting or background for a picture, or for any other material on display in the recess.

In Figure 6, I have illustrated a back plate 12c formed of colored material. The top surface 28c will be exposed through a transparent or translucent cap of any one of the types above described. This back plate has a recess 27c provided with stitching apertures 30 in its bottom, whereby the back plate may be sewed to a garment in the ordinary manner, after which the material to be displayed may be inserted in the recess in a position to cover the stitching, and the cap may then be applied and secured by any suitable means.

25 By employing caps formed of plastic, it is possible to mold the cap rims to the margins of the back plate, in which event the cap plate may be released at any time by applying a suitable solvent to the molded rim.

30 I am aware of the fact that display buttons have heretofore been made with Celluloid or glass covers, protected by form maintaining materials of metal or other opaque substances. Frangible material, such as glass, requires to be covered and protected, whereas caps formed of plastic are non-frangible, do not scratch readily, and are otherwise not subject to any material deterioration or damage. They may be composed of any transparent or translucent plastic, such 40 plastic being made from various substances, and being well-known commercially to persons skilled in the art to which this invention pertains.

It will be understood that the features illustrated in the various modifications are applicable 45 to the structures shown in the other illustrated forms, in a great variety of shapes and sizes, and a great variety of materials may thus be displayed in highly ornamental buttons, and the contents on display may be changed from time 50 to time, particularly when the caps employed are of the snap-on type.

I claim:

1. A button comprising cap and backing members composed of form maintaining, non-frangible substantially incombustible plastic, said backing member being socketed in the rim portion of the cap member and provided with stitching apertures to facilitate securing it to a garment, said cap being transparent, and the inner surface of the backing being provided with a body of relatively opaque material supported by the backing, spaced from the cap, and visible through the central portion thereof, said backing and the

rim portion of the cap being inseparable under ordinary conditions of use.

2. A button comprising a transparent cap of form-maintaining non-frangible, substantially incombustible plastic, a backing secured to the rim portion of the cap, said backing being provided with apertures to facilitate stitching it to a garment and having its margins socketed in the rim portion of the cap, and an intervening body of relatively opaque material supported in a flat 10 position on the backing and visible through the cap, said cap being spaced from said material and forming with the backing an interior cavity of contained material, including sufficient dimensions to avoid compression of fabrics having a 15 pile, such as velvet.

3. A button comprising cap and backing members composed of transparent, form-maintaining, nonfrangible, substantially incombustible plastic, said cap member having a rim adapted for snap- 20 on engagement with the backing, and a central portion spaced from the backing and being of relatively increased thickness, with a convex outer surface adapted to serve as a magnifying lens, a body of relatively opaque material supported upon the interior surface of the backing, and means for preventing said material from shifting on said surface.

4. A button comprising the combination of a transparent cap composed of form-sustaining 30 plastic, a backing formed of form-sustaining plastic socketed in the rim portion of the cap, and an intervening body of material on display, having a soluble plastic connection with the back, said material being spaced from the central portion 35 of the cap.

5. A button comprising the combination of a backing and a transparent cap each composed of form-sustaining plastic, the backing being socketed in the rim portion of the cap, an intervening body or material on display, having a soluble plastic connection with the back and spaced from the central portion of the cap, and a soluble plastic connection between the margin of the backing and the socketed portion of the cap in 45 aid of the gripping action of the cap rim, whereby the cap and backing are inseparable under ordinary conditions of use, while remaining separable for the purpose of substituting material to be displaced.

6. In a button of the described type, a backing having the form of a flat annulus provided with a circular recess in its upper surface, the bottom of which is provided with stitching apertures, in combination with material on display 55 in said recess, and a transparent cap spaced from such material and having a margin in pressure engagement with the backing and normally secured thereto by soluble plastic material to form substantially a one-piece structure, inseparable 60 under ordinary conditions of use.

JOSEPH L. PERELES.
